United States Patent Office

Des. 227,669
Patented July 10, 1973

227,669

AIR CLEANER

Samuel J. Mann, Englewood, N.J., assignor to
Westinghouse Electric Corporation

Filed Sept. 15, 1971, Ser. No. 180,931

Term of patent 14 years

Int. Cl. D23—99

U.S. Cl. D23—149

FIG. 1.

FIG. 2.

FIG. 3.

FIG. 4.

FIG. 1 is a perspective view of an air cleaner embodying my new design showing the top, one side, and front; FIG. 2 is a top plan view thereof;

FIG. 3 is a front elevational view thereof, the rear being a mirror image of the front;

FIG. 4 is an elevational view of the side opposite that shown in FIG. 1.

I claim:

The ornamental design for an air cleaner, as shown and described.
